UNITED STATES PATENT OFFICE.

RONALD ELISON CAMPBELL, OF COLUMBIA, SOUTH CAROLINA, ASSIGNOR TO CHARLES C. WILSON, OF COLUMBIA, SOUTH CAROLINA.

SAFETY ATTACHMENT FOR ELECTRIC IRONS.

1,376,513.

Specification of Letters Patent.

Patented May 3, 1921.

Application filed September 8, 1920. Serial No. 408,917

To all whom it may concern:

Be it known that I, RONALD E. CAMPBELL, a citizen of the United States, and residing at Columbia, Richland county, State of 5 South Carolina, have invented certain new and useful Improvements in Safety Attachments for Electric Irons, of which the following is a specification.

This invention relates to electrically heated 10 implements and particularly to electrically heated sad irons.

One object of the invention is to provide an attachment by means of which an electrically heated iron having the usual manually 15 operable plug and socket connection with the electric mains is converted into an iron having connection with the electric mains through an automatic switch, the electric connection being completed when the handle 20 of the iron is grasped and broken when the handle is released. A feature of this attachment is that it may be quickly adjusted so that the switch is opened or closed either automatically or non-automatically, that is, 25 the circuit may be completed and broken automatically when the handle is grasped and released, or may be completed and broken in the ordinary manner.

Another object is to provide an attachment 30 for a stand upon which the iron is adapted to be placed when not in use, this attachment being adapted to coöperate with the attachment on the iron to prevent the circuit being broken when the iron is on the 35 stand and the handle released, so long as the temperature of the iron is not excessive, but which will release the circuit breaking mechanism of the iron as soon as the temperature of the latter has exceeded a pre- 40 determined degree.

Many forms of electrically heated irons are not provided with automatic features to prevent excessive heating and as a result much damage is done to the iron itself and 45 to any cloth or other object against which the iron may contact in its overheated condition. By using the present invention the overheating of the iron and the burning of valuable articles is prevented. By providing 50 simple and inexpensive attachments to the iron and to its stand respectively, the former is prevented from overheating when on the stand, and its connection to the mains

is automatically broken when it is laid down at any point other than on the stand 55 and its handle released by the operator.

The invention may be embodied in various forms and one satisfactory embodiment will be disclosed in the following description when taken with the accompanying drawings in which:

Figure 1 is a side view partly in elevation and partly in section of a sad iron mounted on its stand, and showing the invention incorporated therewith;

Fig. 2 is a top view of the same;

Fig. 3 is a rear view;

Fig. 4 is a view similar to Fig. 1 but showing the parts in different positions;

Fig. 5 is a perspective view of that portion of the invention which is connected to the stand;

Figs. 6 and 7 are perspective views of portions of that part of the invention which is attached to the sad iron;

Fig. 8 is a section on the line 8—8 of Fig. 4.

The sad iron illustrated has the usual body portion 10, which contains a suitable heating element, (not illustrated) a handle 11, and a separable connection comprising a socket 12 and plug 13, by means of which the heating element of the iron may be connected to the electric mains contained in the cable 14. The stand 15 may be of any well known 80 type and may be of cast iron, sheet metal, or other material.

Secured to the rear post or pedestal of the iron is a metallic cylindrical casing 16 which surrounds the socket member 12 and constitutes a guide for the plug member 13 as it moves into and out of engagement with the socket. The casing 16 is preferably made of sheet metal and its adjacent longitudinal edge portions are spaced and parallel, bolts 17 being provided at the ends to hold the edges of the casing in spaced relation. Bendable flanges 18 at the forward end of the casing are adapted to be bent around the rear pedestal of the handle in the application of the invention to the iron. Extending around the plug 13 and inclosing the same is a cylindrical member 19, also preferably of sheet metal, the end portions of which extend outwardly through the slot between the edge portions of the casing, and

one of these end portions being formed with an upwardly opening groove 19'; clearly illustrated in Fig. 6.

The casing 16 has an interior annular 5 bead 20 formed by externally grooving the same and between this bead or shoulder 20 and the member 19 is located a coiled spring 21 which normally tends to elongate and separate the plug and socket and to break 10 the electrical circuit. Lying in the groove 19' is the rear end of a longitudinally extending rod 22 which extends parallel to the handle and has at its forward end a vertically extending portion hooked at the top 15 and extending around the handle, as shown in Fig. 8. The circular portion extending around the handle is provided with a felt pad 23. This rod is offset near its rear end at 24 and a shoulder thereby formed which 20 is adapted to engage the rear edge of the grooved portion 19.

To the stand is detachably secured a horizontally extending bracket 25, which has pivotally secured thereto an upright member 26. At the forward end of the bracket 25, which is preferably detachably secured 25 to the stand by means of a thumb screw 25', is a hook 27 which is connected to a catch 28 by means of the diagonally extending 30 latch 29 and fusible link 30, which extends through the eye 31 of the latch 29, and around the hook 27. The fusible link 30 is adjacent the lower portion of the face plate of the iron 10 and is designed to melt when 35 the iron, which has been placed on the stand, has exceeded in temperature a certain predetermined degree.

The spring 21 constantly tends, as before described, to separate the members of the 40 separable connector and to thereby break the circuit. When the iron is in use the hand of the operator will prevent the member 23 from sliding rearwardly along the handle and since the member 23 is connected by the rod 22 to the plug holding member 19, the latter is held in the position illustrated in Fig. 1. The plug is also held in this position, and the electrical connection maintained, when the iron is placed on the 45 stand, inasmuch as the member 19 will engage the upper end of the pivoted arm 26, which will prevent rearward motion of the plug under the influence of the spring. If the iron is put down by the operator at 50 any other point, however, and the handle released, it is apparent that the plug 13 will immediately be disengaged from the socket by the spring, inasmuch as no opposition is offered either to the rearward movement of 55 the member 19 or to the rearward movement of the member 23. When placed on the stand the iron will continue to heat until its temperature has reached an undesirable degree, when the fusible link 30 will melt, releasing the latch 29 and allowing the plug 60

to be forced rearwardly by the spring to break the connection.

If, when the iron is being used, it is found to be too hot for certain classes of work, the rod 22 may be adjusted to allow the 70 spring 21 to break the connection. To effect this adjustment it is only necessary to raise the rod 22 slightly so that the shoulder at 24 will disengage the edge of the member 19. In this manner the iron may be instantly adjusted so that the circuit will be broken automatically under the conditions stated, or may be adjusted for ordinary manual manipulation of the circuit breaking device. 80

It will be apparent from the above description that the invention is of great simplicity and adaptability, that it may be made with small expense, and in many forms to be applied to different kinds of 85 irons and supporting stands, and that it provides means whereby the overheating of the iron through accident or neglect is positively prevented, either when the iron is placed on the stand or is laid down at some 90 other point.

Having thus described my invention what I claim as new and desire to secure by Letters Patent is:—

1. The combination with an electrically 95 heated device having a separable electric connection adjacent the same, of means for closing said connection when the handle is gripped and opening the same when the handle is released, said means including a 100 member movable longitudinally of the handle by the hand of the operator.

2. The combination with an electrically heated device having a separable electric connection adjacent the same, of means for 105 closing said connection when the handle is gripped and opening the same when the handle is released, said means including a member movable longitudinally of the handle by the hand of the operator, and a 110 spring for moving said member in one direction and simultaneously parting the electrical connection.

3. The combination with an electrically 115 heated device having a separable electric connection adjacent the same, of means for closing said connection when the handle is gripped and opening the same when the handle is released, said means including a 120 member movable longitudinally of the handle, a spring, and connections between said member and spring whereby the latter is put under strain when the former is moved by the hand.

4. The combination with an electrically 125 heated device having a separable electric connection adjacent the same, of means for closing said connection when the handle is gripped and automatically opening the same when the handle is released, said means be- 130

ing adapted to be adjusted to prevent the closing of the connection when the handle is gripped, if desired.

5. The combination with an electrically heated device having a separable electric connection, of means for closing said connection when the handle is gripped and opening the same when the handle is released, said means including a member 10 adapted to be moved by the hand of the operator when the handle is grasped, a spring, and means normally connecting said member and spring whereby the latter is put under strain when the former is moved, 15 said means being readily disconnectible, for the purpose set forth.

6. The combination with an electrically heated device having a separable electric connection, of means for closing said connection when the handle is gripped and opening the same when the handle is released, said means comprising a member 20 movable longitudinally of the handle, a spring, and connections between said member and spring including a rod having a hooked portion, whereby the spring is put under strain when said member is moved, 25 said rod being arranged to be disconnected, for the purpose set forth.

30 7. The combination with an electrically heated device having a handle and a separable electric connection adjacent the same, of a stand therefor, means on the electrically heated device adapted to break the 35 electric connection when the handle is released by the operator, and means on the stand for preventing said first mentioned means from becoming operative when the device is placed thereon and the handle released, said means including a 40 fusible link adapted to melt to release the connection breaking means when the iron becomes overheated.

8. The combination with an electrically heated iron having a handle and a separable electric connection adjacent the same, of a stand therefor, means including a spring 45 on the iron for breaking the electric connection when the handle is released by the operator, and means on the stand for preventing said spring from operating to break the connection when the iron is placed thereon and the handle released. 50

9. The combination with an electrically heated device having a handle and a separable electric connection adjacent the same, of a stand therefor, means on the electrically heated device adapted to break the 55 electric connection when the handle is released by the operator, and means on the stand for normally preventing said first mentioned means from becoming operative when the device is placed thereon and the 60 handle released, but which will release the connection breaking means when the iron becomes overheated.

10. The combination with an electrically heated device having a handle and a separable electric connection adjacent the same, of a stand therefor, means on the electrically heated device adapted to break the 65 electric connection when the handle is released by the operator, and means on the stand for normally preventing said first mentioned means from becoming operative when the device is placed thereon and the 70 handle released, said means including a fusible link adapted to melt to release the 75 connection breaking means when the iron becomes overheated.

In testimony whereof I affix my signature.

RONALD ELISON CAMPBELL.
